Primary Examiner — Jasmine Mlinarcik*Assistant Examiner* — James P McKane(74) *Attorney, Agent, or Firm* — WPAT, PC(57) **CLAIM**

The ornamental design for a pair of gloves, as shown and described.

DESCRIPTION

FIG. 1 is a front view of the pair of gloves, showing my new design; and,

FIG. 2 is a rear view.

The broken lines shown are included for the purpose of illustrating portions of the pair of gloves which form no part of the claimed design.
